CLAIM

The ornamental design for a safety harness with American flag design, as shown and described.

DESCRIPTION

FIG. 1 is a front elevational view of a safety harness with American flag design showing the new design;

FIG. 2 is a back elevational view of the safety harness with American flag design of FIG. 1;

FIG. 3 is a right-side elevational view of the safety harness with American flag design of FIG. 1;

FIG. 4 is a left-side elevational view of the safety harness with American flag design of FIG. 1;

FIG. 5 is a front perspective view of the safety harness with American flag design of FIG. 1; and,

FIG. 6 is a back perspective view of the safety harness with American flag design of FIG. 1.

The broken lines shown in the drawings illustrate unclaimed portions of the claimed design and form no part of the claimed design.
